[57] CLAIM

The ornamental design for a portable computer, as shown and described.

DESCRIPTION

FIG. 1 is a top, front and right side perspective view of a portable computer having its cover opened to an operating position and the legs retracted showing my new design;

FIG. 2 is a front elevational view thereof with the legs retracted;

FIG. 3 is a rear elevational view thereof with the connector panel closed and the legs retracted;

FIG. 4 is a top plan view thereof;

FIG. 5 is a bottom plan view thereof with the connector panel closed and the legs retracted;

FIG. 6 is a right side elevational view thereof with the legs retracted;

FIG. 7 is a left side elevational view thereof with the legs retracted;

FIG. 8 is a top, front and right side perspective view thereof with the cover closed;

FIG. 9 is a top, rear and right side perspective view thereof with the cover closed and the connector panel closed;

FIG. 10 is a top, rear and right side perspective view thereof with the cover closed and the connector panel open; and,

FIG. 11 is a right side elevational view thereof with the legs extended.

FIGS. 2-11 are drawn on an enlarged scale.

FIG. II

FIGS. 1-2

FIG. 4
